COMBINED CLEANING AND WAXING MACHINE FOR FLOORS OR THE LIKE

Robert I. Lappin, Marblehead, Mass.
(% Signal Mfg. Co., 69 Bennett St., Lynn, Mass.)

Filed Jan. 21, 1959, Ser. No. 54,259

Term of patent 14 years

(Cl. D9—2)

Fig. 1 is a front perspective view of a combined cleaning and waxing machine for floors or the like embodying my new design;

Fig. 2 is a rear perspective view thereof;

Fig. 3 is a perspective view thereof as seen from the left of Fig. 1;

Fig. 4 is a perspective view thereof as seen from the right of Fig. 1; and

Fig. 5 is a section on line 5—5 of Fig. 1.

I claim:

The ornamental design for a combined cleaning and waxing machine for floors or the like, substantially as shown.
